I. E. MATHESON

TOBOGGAN SLIDE

Filed June 2, 1923

JAN E. MATHESON.

BY *Fetherstonhaugh & Co* ATT'Y'S.

UNITED STATES PATENT OFFICE.

IAN EUICHIN MATHESON, OF RADVILLE, SASKATCHEWAN, CANADA.

TOBOGGAN SLIDE.

Application filed June 2, 1923. Serial No. 643,099.

To all whom it may concern:

Be it known that I, IAN EUICHIN MATHESON, a subject of the King of Great Britain, and resident of the town of Radville, in the 5 Province of Saskatchewan and Dominion of Canada, have invented certain new and useful Improvements in Toboggan Slides, of which the following is a specification.

This invention relates to improvements in 10 toboggan slides and more particularly to water toboggan slides, and the objects of the invention are to provide a slide of this kind specially adapted for imparting speed to the travel of a toboggan while at the same time 15 providing means for securing the toboggan against accident by falling off the slide.

Still further objects are the provision of a slide of this character provided with an extension adapted to float or rest upon water and to receive the toboggan after it leaves the runway or slide and direct its course as nearly parallel to the water as possible.

With the foregoing and other objects in 25 view, the invention consists essentially in the novel construction and arrangement of parts described in the present specification and illustrated in the accompanying drawings that form part of the same.

Referring now to the drawings, in which like characters of reference indicate corresponding parts in each figure,

Figure 1 is a longitudinal section of the toboggan slide.

Figure 2 is a top plan view.

Figure 3 is a section on the line 3—3 of Figure 2.

Figure 4 is a section on the line 4—4 of Figure 2.

In the drawings, A designates an embodiment of my improved toboggan slide as a whole constructed of any suitable material and comprising a platform 10 suitably joined to an inclined plane or runway 11, the platform and runway being supported by a plurality of suitable uprights 13 provided with braces 14 and the platform being further protected by a guard railing 15.

Hingedly connected to the lower end of 50 the runway 11 is an extension 16 designed to float, as here shown, on the water. This

extension is preferably built of light material and is made water-tight to catch a toboggan after it leaves the runway.

17 are flanges on each side of the runway 55 11 designed to prevent a toboggan in its travel from falling off.

18 are a plurality of transversely extending rollers arranged at spaced intervals in the runway 11 and platform 10. These rollers are preferably constructed of wood with iron collars 19 on each end and an iron rod 20 running through the centre and adapted to operatively engage the sides 21 of the runway.

Alternately mounted between the rollers 18 are a plurality of grooved wheels 22 at opposite sides on the runway.

This combination of wheels and rollers is to assist the downward travel of the toboggan and the arrangement of the wheels is as follows:

A suitable rod 23 connects both sides of the runway and on it is mounted a grooved wheel at each end and adapted to hold the 75 runners of the toboggan and, like the rollers, to add to the downward speed of the toboggan.

As many changes could be made in the above construction and many apparently 80 widely different embodiments of my invention within the scope of the claims, constructed without departing from the spirit or scope thereof, it is intended that all matter contained in the accompanying specification and drawings shall be interpreted as 85 illustrative and not in a limiting sense.

What I claim as my invention is:

1. A toboggan slide of the character described comprising a platform and runway 90 provided with suitable supporting means and a hinged extension on the runway adapted to catch a toboggan after it has left the slide, water-proof means for said extension whereby it is designed to float, a plurality of transversely extending rollers operatively mounted at spaced intervals in the runway, a plurality of grooved wheels operatively and alternately mounted between said rollers in the runway and adapted to rotatably 95 engage with the toboggan runners whereby in combination with said rollers the speed 100

of the toboggan is increased and guard means on the runway sides.

2. In a device of the character described and in combination with a suitably supported platform and a runway, a pivotally mounted extension for the runway and roller and guide wheel means carried by the runway for increasing the speed of a toboggan, guard means for holding the toboggan

on the runway and a guard rail for the platform.

In witness whereof I have hereunto set my hand in the presence of two witnesses.

IAN EUICHIN MATHESON.

Witnesses:

M. L. M. SKELTON,
U. ANDERSON.
